UNITED STATES PATENT OFFICE.

LOUIS W. GATES, OF NEW HAVEN, CONNECTICUT, ASSIGNOR TO C. COWLES & COMPANY, OF NEW HAVEN, CONNECTICUT, A CORPORATION OF CONNECTICUT.

DOOR HANDLE.

Application filed September 1, 1923. Serial No. 680,519.

To all whom it may concern:

Be it known that I, LOUIS W. GATES, a citizen of the United States, residing at New Haven, county of New Haven, State of Connecticut, have invented a new and useful 5 Door Handle, of which the following is a specification.

This invention relates to latch operating handles, particularly of the type which are 10 used on vehicles doors, and has for an object to provide a handle of this type which will be simple in construction, requiring but a few parts, which may be manufactured at low cost, which will not be easily gotten out 15 of order and so will be reliable and efficient in operation, which may be applied to the door without fitting or require recessing the surface of the door, in which the escutcheon will lie flush with the surface of the door, 20 and which will be neat and attractive in appearance.

With the foregoing and other objects in view, I have devised the construction illustrated in the accompanying drawing, in 25 which

Fig. 1 is a vertical section through a portion of a door and the escutcheon in position thereon, the handle being shown in elevation.

30 Fig. 2 is a front elevation of the escutcheon and a cross section through the stem of the handle substantially on line 2—2 of Fig. 1.

Figs. 3 and 4 are detailed cross sectional views substantially on line 4—4 of Fig. 1, 35 showing the means for securing the elements to the latch spindle, Fig. 3 showing the securing element applied to the spindle but not secured thereon and Fig. 4 showing how it is secured to the spindle.

40 At 10 I have shown a section of a portion of a vehicle or other door having an opening 11 through which the square latch operating spindle 12 extends to any suitable type of latch, not shown, as it forms no part 45 of my present invention. Secured to the outer end of the spindle 12 is any suitable type of operating handle 13.

For securing the handle to the door and giving a neat and attractive appearance, an escutcheon plate 14 is provided which is 50 adapted to be fastened to the surface of the door by any suitable means such as screws 55. This escutcheon plate is preferably pressed from sheet metal and is provided with an outwardly extending substantially

spherical flange 16 which is convex on its outer surface and concave on its inner surface forming a recess. It is also provided with a central opening 17 through which the latch operating spindle extends. Mounted 60 upon the spindle 12, and preferably forming a part of the stem 18, is a collar or member 19 providing a shoulder to engage the outer surface of the flange 16, and in order to give a neat and attractive appearance 65 and provide a better bearing upon this surface, the face of this collar or member is provided with an annular groove 20 having its inner wall substantially spherical or concaved to fit the outer convex surface of the 70 flange, and the portion 21 of the member 19 at the inner side of this concave surface is of a smaller diameter than the opening 17 to allow lateral or rocking movement of the stem with respect to the escutcheon for 75 a purpose which is presently to be described.

On the other side of the flange 17 and located in the recess formed thereby is a coil spring 22 which engages the concave wall of the flange at one end and a collar or washer 23 at the other end. This collar or washer is also preferably provided with an annular flange 24 extending into the spring to give a better bearing on the spindle and also a better support for the outer end of the 80 spring. The collar 23 and the spring 22 may be secured in position by various means but I prefer that substantially as shown. In this securing means the spindle 12 is provided on opposite sides thereof in proper position, a pair of transverse grooves 25, and a split securing washer 26 is used as a securing 85 element. This washer is formed, as shown in Fig. 3, with the ends 27 on opposite sides of the split separated a sufficient distance so 90 that it may be slid transversely onto the spindle from one side thereof. These ends are then pressed together pressing the sides 28 into the grooves 25, and the shoulders 29 will then engage on one side of the spindle, 95 as shown in Fig. 4, and securely hold the element in position on the spindle. The element will then be securely fastened to the spindle and will be held against longitudinal 100 movement thereon by the grooves 25. The 105 grooves 25 and the concave surface of the groove 20 are so located with respect to each other that when the elements are in position, as shown in Fig. 1, the spring 22 is under compression and its reaction against the con- 110

cave surface of the flange 16 and collar 23 will tend to hold the concave surface of groove 20 against the outer or convex surface of the flange 16. If when applying 5 the handle to a door the surface of the door should not be normal or at right angles to the axis of the spindle, the escutcheon may rock with respect to the spindle and lie flush with the surface of the door, thus giving a 10 good fit and appearance. The action of the spring 22 also gives a good bearing between the escutcheon and the collar 19 and will always maintain it tight and automatically take up any wear which will occur between 15 these elements incident to the operation of the handle. Thus the bearing between the escutcheon and the handle will always be snug and there will be no liability of its becoming loose and rattling. It will also be 20 apparent from an inspection of Fig. 1 that all of the securing elements are mounted within the confines of the escutcheon plate. In other words when the plate is fastened to the surface of the door they are all outside 25 of this surface so that it is not necessary to cut a recess in the door to receive these securing elements. The only cutting necessary on the door being that required to bore the opening 11 for the passage of the spindle.

30 Having thus set forth the nature of my invention, what I claim is:

1. In a device of the character described, an escutcheon plate adapted to be secured to a door and provided with a laterally extending concavo-convex flange having an 35 opening therethrough, a latch operating spindle extending through said opening, said spindle carrying a shoulder engaging one side of said flange, a spring engaging 40 the other side of the flange, and means secured to the spindle forming an abutment for the other end of the spring.

2. In a device of the character described, an escutcheon adapted to be secured to a 45 door and provided with a laterally extending concavo-convex flange having an opening therethrough, a latch operating spindle extending therethrough, spaced elements carried by said spindle on opposite sides of 50 the escutcheon, one of said elements engaging the convex wall of said flange, and a spring between the flange and the other element and reacting against them to hold the first element in engagement with said flange.

55 3. In a device of the character described, an escutcheon adapted to be secured to a door and provided with a laterally extending substantially spherical flange convex on its outer surface and concave on its inner surface, said flange being provided with an 60 opening therethrough, a latch operating spindle extending through said opening and carrying a concave shoulder engaging the outer wall of said flange, an element forming an abutment secured to the spindle in-

wardly of the flange, and a coil spring between said abutment and the concave side of said flange.

4. In a device of the character described, 70 an escutcheon adapted to be secured to a door, said escutcheon being provided with an outwardly extending flange substantially spherical on its outer surface and provided with an opening therethrough, a latch operating spindle extending through said opening and carrying a concave shoulder adapted to engage the outer wall of said flange, an abutment carried by the spindle on the other side of the escutcheon, and a spring reacting at its opposite ends between the abutment 75 and the escutcheon.

5. In a device of the character described, 80 an escutcheon adapted to be secured to a door, said escutcheon being provided with an outwardly extending flange substantially spherical on its outer surface and provided with an opening therethrough, a latch operating spindle extending through said opening and carrying a concave shoulder adapted to engage the outer wall of said flange, an abutment carried by said spindle on the other side of the escutcheon, and a coil spring 85 embracing the spindle and bearing at its opposite ends against the escutcheon 90 and the abutment.

6. In a device of the character described, 95 an escutcheon adapted to be secured to a door, said escutcheon being provided with an outwardly projecting concavo-convex flange having a substantial spherical outer 100 surface and providing a pocket on the inner side, said flange being provided with an opening, a latch operating spindle extending through said opening, spaced abutments carried by the spindle on opposite sides of 105 the escutcheon, the outer abutment being provided with a concave substantially spherical surface engaging the outer surface of the flange and a coiled spring embracing 110 the spindle in said pocket and reacting at its opposite ends against the concave surface of the escutcheon and the other abutment.

7. In a device of the character described 115 an escutcheon adapted to be secured to a door and provided with an opening, a latch operating spindle extending through said opening, spaced elements embracing said spindle and engaging the opposite sides 120 of said escutcheon, said spindle being provided with a transverse groove on one side thereof, and a securing element comprising a split washer embracing the spindle and seated in said groove.

8. In a device of the character described 125 an escutcheon adapted to be secured to a door and provided with an outwardly extending concavo-convex flange having an opening therethrough, a latch operating spindle extending through said opening, a handle secured to said spindle and provided 130

- with a concave shoulder engaging the outer surface of said flange, a coil spring embracing the spindle and engaging the other surface of the flange, said spindle being provided with transverse grooves on opposite sides thereof, and a securing element at the other end of the spring comprising a split washer embracing the spindle and seated in said grooves.
9. In a device of the character described, an escutcheon adapted to be secured to a door and provided with an outwardly extending substantially spherical flange convex on its outer surface and concave on its inner surface, said flange being provided with an opening therethrough, a latch operating spindle extending through said opening and carrying a shoulder engaging the outer wall of said flange, an element forming an abutment secured to the spindle inwardly of the flange, and a spring between said abutment and the concave side of the flange, said spring and abutment being located outside the door engaging face of the escutcheon.
10. In a device of the character described, an escutcheon adapted to be secured to a door, said escutcheon being provided with a laterally extending concavo-convex flange having an opening therethrough, a latch operating spindle extending through said opening, spaced elements carried by said spindle on opposite sides of the escutcheon, one of said elements engaging one side of said flange, and a spring between the flange and the other element arranged to hold the first element in engagement with said flange, said elements and spring being located outside the door engaging face of the escutcheon.
11. In a device of the character described, an escutcheon adapted to be secured to a door with its inner face engaging the surface of the door, said escutcheon being provided with a lateral substantially spherical extension having an opening therethrough, a latch operating spindle extending through said opening and carrying a shoulder engaging the outer surface of said extension, a stop means carried by the spindle on the other side of said extension, and a resilient element between the escutcheon and said latter stop means, said resilient element and the stop means being located outside the door engaging face of the escutcheon.
12. In a device of the character described, an escutcheon having its inner face constructed for contact with the surface of a door or the like, means for securing the escutcheon to a door, a latch spindle extending through said escutcheon, and means carried by the escutcheon and spindle for securing the spindle to the escutcheon arranged to allow relative rotary and angular movements between the escutcheon and the spindle, the whole of said latter securing means being located entirely outside the door engaging face of the escutcheon.

In testimony whereof I affix my signature.

LOUIS W. GATES.
